UNITED STATES PATENT OFFICE

WILLIAM C. McWHIRTER, OF WILKINSBURG, AND JAMES E. SPEER, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA

TIME-GOVERNED CIRCUIT-CONTROLLING MECHANISM

Application filed December 11, 1926. Serial No. 154,291.

Our invention relates to time governed circuit controlling mechanisms.

More particularly our invention relates to improvements in the clockwork time release mechanisms shown and described in United States Patent No. 992,236 issued to W. P. Neubert and W. S. McClelland, Jr., on May 16, 1911.

One object of our invention is to provide a mechanism wherein the time interval between the operation of different sets of contacts controlled by the mechanism may be varied by means external to the enclosing casing of the mechanism.

We will describe two forms of mechanisms embodying our invention, and will then point out the novel features in claims.

In the accompanying drawings Fig. 1 is a side elevation, partly in section, showing one form of mechanism embodying our invention. Fig. 2 is section taken on the line II-II of Fig. 1. Fig. 3 is a plan view of a portion of the mechanism shown in Figs. 1 and 2. Fig. 4 is a detail view of another portion of the mechanism shown in Figs. 1 and 2. Figs. 5 and 6 are side and front elevations, respectively, partly sectioned, of a modification of the mechanism shown in Figs. 1 and 2.

Similar reference characters refer to similar parts in each of the several views.

Referring first to Fig. 1, the reference character 5 designates a base plate upon which the various parts of the mechanism are mounted. Secured to the base plate by means of screws 9 is a plate 7. A second plate 6 is secured to plate 7 by means of studs 8 and the parts of the clock-work mechanism described in the patent mentioned above are mounted between these plates. Since the parts of this mechanism form no part of our invention, we have shown only the driving spring 11 one end of which is secured to the inside of a spring-cage 10 and the other end of which is secured to a shaft 12. One end of shaft 12 is journaled in a recess 22^a in the end of a second shaft 22 to which spring-cage 10 is secured. The other end of shaft 12 is secured in the base-plate 5. A bracket 13 secured to the base plate by means

of screws 14 acts as a bearing for shaft 22. Journaled in the upstanding end of the bracket 13 is a member 15 having a depending lug 17 integral therewith and also having a socket 21 therein. The member 15 is rotatably mounted within the bracket 13 and may be actuated by means of a knob 38. The shaft 22 has one end journaled in the plate 6 while the other end fits into the socket 21 in member 15. Fixed to the shaft 22 by means of a pin 23 is a sleeve 24, which carries an arm 25. The sleeve 24 has a reduced portion 24^a with a conical surface against which is secured another sleeve 33 having a portion fitting the part 24^a and held in place by a nut 34. The sleeve 33 carries an integral cam 31, an arm 26 and also two stop members 32 and 46. The stop member 32 co-operates with lug 17 and also with a stop 19 which will be described hereinafter. The member 15 is reciprocal and has its longitudinal position defined by means of a ball ratchet 16 which may engage either of two grooves 16^a or 16^b in member 15. When the knob 38 is rotated in a clock-wise direction (looking from right to left in Fig. 1) the lug 17 engages the lug 32 on sleeve 33 so that arms 25 and 26 and also cam 31 are rotated in a clock-wise direction. In its extreme position to the right, the arm 26 engages a stop 20 which is formed integral with the bracket 13 (Fig. 3), and when in the extreme left-hand position the arm 25 engages a similar stop 18.

Mounted upon the bracket 13 and suitably insulated therefrom are contacts 27-28 and 29-30 which co-operate with arms 26 and 25, respectively, and may be connected to suitable electrical circuits by means of terminal posts 47. Secured to the plate 6 are two contact members 35 and 36 which may be closed by means of a pivoted member 37 mounted in the path of cam 31. The number of contacts which we have shown is merely for the purpose of explanation and any suitable number of circuits may be controlled in any desired manner. The pressure of the contact arms 25 and 26 upon the contact springs is limited by means of the stops 18 and 20. Secured to the arm 26 is a pointer 35 which moves over a graduated dial 40 and indicates

the position of the contact-operating members.

The entire mechanism is protected from dirt by means of a glass cover 48 which is secured in place in any suitable manner.

For the purpose of locking the mechanism in one position the bracket 13 carries a lug 41 upon which is pivotally mounted a latch 43 by means of a pin 42. The latch 43 has a notch 44 and when this latch occupies the position shown in Fig. 2 of the drawing, spring 45 urges the latch 43 into such a position that notch 44 and lug 46 engage to prevent rotation of shaft 22. With the parts in this position the lug 17 on member 15 may engage the latch 43 but is held a short distance away from the stop 19 so that when the handle 38 is turned in a counter clockwise direction the latch 43 will be disengaged from the lug 46.

In describing the operation of the mechanism we will assume that the parts occupy the positions shown in the drawing, with the latch 43 engaging the lug 46 and preventing rotation of the shaft 22 and its associated mechanism by the spring 11 which is under tension. When release of the mechanism is desired for the purpose of opening contact 27-28 and closing contact 35-36 the knob 38 is turned slightly to the left forcing the lug 17 on member 15 against the latch 43 so that the lug 46 on member 33 is disengaged from the notch 44, thus allowing arms 25 and 26 and cam 31 to be rotated in a counter clockwise direction by spring 11. After a predetermined interval cam 31 will engage member 37 so that contact 35-36 is closed. When the cam 31 reaches the member 37 the lug 17 will be between the stop 19 and the lug 32 on sleeve 33 and will arrest the motion of shaft 22 as well as the arms 25 and 26 and the cam 31. If it is now desired to wind the spring and return the parts to normal position, the knob 38 is turned in a clock-wise direction. The lug 17 engaging lug 32 will rotate cam 31 and arms 25 and 26 until arm 26 closes contact 27-28 and engages the stop 20. In this position latch 43 will again engage the lug 46 to hold the parts at rest.

If it is desired to open the contact 27-28 and after a time interval close the contact 29-30, the knob 38 is moved outwardly so that ball ratchet 16 engages the groove 16^b and the handle is turned slightly to the left to disengage the latch 43. The shaft 22 will now rotate in a counter clock-wise direction rotating arms 25 and 26 and the cam 31. After a time interval the cam 31 will engage the member 37 closing contact 35-36 but since the lug 17 has been pulled outwardly it will not engage the lug 32 and therefore the parts will continue to rotate, the contact 35-36 remaining closed during the time in which cam 31 engages the member 37, and then opening as this cam leaves the member

37. After further rotation the arm 25 will close contact 29-30 and will then engage the stop 18. The contact 29-30 will remain closed until the knob 38 is again turned in a clock-wise direction, whereupon the lug 17 engages arm 25 and so restores sleeve 24, shaft 22 and sleeve 33 to their initial positions.

It will now be seen that the operation of the different sets of contacts may be controlled from the outside of the casing by placing the knob 38 in proper position, also that the time intervals between the operations of the different contacts may be varied to suit specific requirements by a proper proportioning of lug 32 and cam 31 as well as by adjustment of sleeve 33.

The mechanism which we have just described may be termed the "normally wound" type, that is, when the device is not in actual use the actuating spring is wound up as far as any winding on the part of the operator is concerned. The contact 27-28 remains closed and the arm 26 engages the stop 20. The parts are held in this position by the engagement of latch 43 and lug 46. Another type of mechanism which is sometimes desirable is one in which the spring is "normally unwound" and is set in operation by winding the spring. A mechanism of the latter type is shown in Figs. 5 and 6.

In the mechanism shown in Figs. 5 and 6 the contact 35-36 is controlled by a cam 25 secured to sleeve 24. Sleeve 24 also carries an arm 26 for co-operation with contact 29-30, and a lug 26^a which engages the stop 18 when the parts are in normal position as shown in the drawing. An arm 31 secured to the sleeve 33 operates the contact 27-28 when the shaft 22 is moved to the extreme right-hand position (Fig. 6). The sleeve 33 also carries an integral lug 52 which cooperates with a stop 51 on the bracket 13, and limits the rotation of the sleeve 33 in a clock-wise direction. It will, therefore, be clear that when the arm 31 is rotated clockwise until it operates contact 27-28, the lug 52 will engage the stop 51 and will prevent further rotation of the parts in this direction. The member 15 in this form of the invention has a sleeve portion 49 which carries two integral lugs 17^a and 50. The shaft 22 and the parts secured thereto are driven by a spring as in Fig. 1 but the spring is omitted from Figs. 5 and 6 for the sake of simplicity.

If it is desired to close the contact 27-28 and then after a predetermined time interval to close contact 29-30, starting from the position shown in Fig. 6, the knob 38 is rotated in a clock-wise direction until lug 52 engages the stop 51 and arm 31 closes the contact 27-28. During this movement the shaft 22 and the parts carried thereby are driven by the engagement of lug 50 with lug 26^a. The lug 17^a will not engage the stop 19 during this rotation because the mem-

ber 15 is in its left-hand position so that ratchet 16 engages the groove 16^a. As soon as the knob 38 is released, the cam 25 and arms 26 and 31 commence to rotate in a counter clock-wise direction under the action of the spring which rotates shaft 22. During this rotation the cam 25 will close contact 35—36 and will hold it closed as long as the cam engages member 37. The rotation of the parts 10 continues until lug 26^a again engages stop 18 and arm 26 closes contact 29—30.

If it is desired to close contact 35—36 and after a time interval re-close contacts 29 and 30 the knob 38 is moved into its right hand 15 position in which the ratchet 16 engages groove 16^b. When the knob 38 is now moved in a clock-wise direction (Fig. 6) the rotation can continue only until lug 17^a engages the stop 19, at which point the cam 25 will 20 engage member 37 closing contact 35—36. When the knob 38 is released the cam 25 and arms 26 and 31 will rotate in a counter clock-wise direction opening contact 35—36. The rotation of the parts will continue until after 25 a time interval, lug 26^a engages stop 18 and arm 26 closes contact 29—30.

It will be obvious that by changing the relative positions of sleeves 24 and 33 the time intervals between the operations of contacts 27—28 and 29—30 may be varied.

We have shown both forms of mechanism as provided with a knob 38 for hand operation but it will be understood that the device may equally well be operated by mechanical attachment to an interlocking machine.

Although we have herein shown and described only two forms of circuit controlling mechanisms embodying our invention it is obvious that various changes may be made therein within the scope of the appended claims without departing from the spirit and scope of our invention.

Having thus described our invention, what 45 we claim is:

1. A circuit controlling mechanism comprising two sets of contacts, a rotatable arm for operating one set of contacts and a cam for operating the other set, a stop member secured to the cam, a longitudinally movable member for engaging said stop and limiting the movement of the associated cam to operate one set of contacts or both sets of contacts in succession, according as said member 55 is or is not in position to engage said stop.

2. A circuit controlling mechanism comprising two angularly displaced sets of contacts, a first and a second rotatable sleeve secured together, one having a cam for operating one set of contacts and the other an arm for operating the other set of contacts, a stop on the first sleeve, a longitudinally movable member carrying a lug for engaging the stop, and means for actuating the sleeves to operate the contacts associated with the cam when

the member is in one position and to operate the two sets of contacts in succession when the member is in the other position.

3. A circuit controlling mechanism comprising two angularly spaced sets of contacts, a longitudinally movable two-position member having a lug thereon, a stop for engaging the lug when the member is in one of said positions only and rotatable actuating means for operating one set of contacts when the member is in such position that the lug engages the stop, but for operating the two sets of contacts in succession when the member is in the other position.

4. A circuit controlling mechanism comprising a casing, a plurality of sets of contacts within said casing, means for selectively operating said sets of contacts, and means outside of said casing for controlling the selection of the contacts to be operated.

5. A circuit controlling mechanism comprising a plurality of angularly displaced sets of contacts, rotatable means for selectively operating said sets of contacts, a longitudinally movable member having two lugs thereon, stationary means co-operating with one of said lugs for limiting the movement of the rotatable means and means co-operating with other lug for actuating the rotatable means.

6. A circuit controlling mechanism comprising a plurality of angularly displaced sets of contacts, rotatable means for selectively operating said sets of contacts, a support, a member slidable in said support and having two lugs thereon, a stop on the support for engaging one of said lugs to limit the movement of the rotatable means and a lug on the rotatable means for engaging the other lug to actuate the rotatable means.

7. A circuit controlling mechanism comprising a casing, a plurality of angularly displaced sets of contacts within said casing, rotatable means for operating said sets of contacts, means for limiting the rotation of said operating means, and means outside of the casing for controlling the limiting means.

8. A circuit controlling mechanism comprising rotatable contact operating means including a lug, a stationary support, a stop on said support, an enclosing casing, and means operable from outside the casing and slidably in said support for engaging said lug and said stop to limit the movement of the contact operating means.

9. A circuit controlling mechanism comprising rotatable contact operating means including a lug, a stationary support, a stop on said support, an enclosing casing, a member slidable in said support, means on said member for engaging said lug and said stop to control the amount of rotation of the contact operating means, and means operable from the outside of the casing for moving said member.

10. A circuit controlling mechanism comprising a casing, a plurality of angularly displaced sets of contacts within said casing, rotatable means for operating said sets of contacts, a lug on the rotatable means, a stationary support, a member slidable in said support, a lug on said member, means for holding the member in either of two positions, and means operable from outside of the casing for causing the lug on said member to engage or not to engage the lug on the rotatable means according as said member occupies one or the other of its positions.
11. A circuit controlling mechanism comprising a shaft biased to turn in one direction, a manually operable member co-acting with said shaft to turn the shaft in the other direction, said member being capable of longitudinal motion with respect to said shaft, means responsive to variations in the longitudinal position of said member with respect to said shaft for varying the amount of movement of the shaft, and circuit controlling contacts governed by said shaft.
12. A circuit controlling mechanism comprising a shaft biased to turn in one direction, a manually operable member co-acting with said shaft to turn the shaft in the other direction, to a given position, said member being capable of longitudinal motion with respect to said shaft, means responsive to variations in the longitudinal position of said member with respect to said shaft for varying the position to which the shaft returns under the influence of the biasing means, and circuit controlling contacts governed by said shaft.
13. A circuit controlling mechanism comprising a shaft biased to turn in one direction, a manually operable member co-acting with said shaft to turn the shaft in the other direction, said member being capable of longitudinal motion with respect to said shaft, means responsive to variations in the longitudinal position of said member with respect to said shaft for varying the position to which said shaft may be turned by said member, and circuit controlling contacts governed by said shaft.
14. In testimony whereof we affix our signatures.

WILLIAM C. McWHIRTER.
JAMES E. SPEER.
